VANE TYPE HYDRAULIC MOTOR

Oscar E. Rosaen, Detroit, Mich.

Application December 6, 1946, Serial No. 715,181

3 Claims. (Cl. 121—92)

2

The present invention relates to hydraulic motors and specifically to reversible rotary motors of the vane type.

In motors of this type as heretofore known, one of the difficulties encountered has been the control of the vanes in their radial movement in the rotor. Accordingly one of the objects of the present invention is to provide an efficient control for the vane movement in both "forward" and reverse rotation.

Another object is to provide means for causing positive instant outward movement of the vanes when pressure fluid is admitted to drive the motor in either direction.

Another object is to provide means for causing positive inward movement of the vanes after they have been relieved of the driving pressure and as they move into the fluid outlet zone.

Still other objects and advantages will be apparent to those skilled in the art upon reference to the following description and the accompanying drawings in which

Fig. 1 is central longitudinal sectional view of the motor as if on line 1—1 of Fig. 4.

Fig. 2 is a view in elevation of one of the face plates.

Fig. 3 is a similar view of the opposite side of said plate.

Fig. 4 is a sectional view normal to the axis of the motor and showing the rotor and enclosing ring.

Fig. 5 is a perspective view of the ring showing means for obtaining a balanced flow of oil to the operating chambers formed by ring and rotor (18A).

Figs. 6 and 7 are respectively an end view and a central sectional view of a detail.

Fig. 8 is a perspective view of one of the vanes.

As indicated in the drawings, the motor comprises the two end members 10 and 10A which are alike on their inner or opposed faces in that each is provided with a circular recess 11 surrounded by a heavy flange 12, and in each is an annular chamber into which open the fluid passages and threaded connections 14. The end members 10 and 10A are provided with aligned axial passages for the reception of the motor shaft 15, these passages being enlarged in their outer end portions to receive the nuts 16 and bearings 17 and 17A in which the shaft 15 is mounted.

In member 10, the bearing 17 is preferably covered by means of a suitable cap 17B, provided with a tapped opening 17C serving as a drain for the shaft enclosing space.

The member 10A is arranged to mount a suit-

able mounting flange 18 and through this extends the splined end of shaft 15.

Between the opposed faces of members 10 and 10A and in the recesses 11 are the working and fluid directing elements of the motor. These consist of the ring element 28, the rotor 19 and the two face plates 20R and 20L, the latter and the ring element 28 having a combined thickness slightly greater than the combined depth of the recesses 11 so that when the members 10 and 10A are fixed together as by screws 10B, these members 10 and 10A are slightly spaced as shown and leakage prevented by a small gasket 10C. The rotor 19 lies within the ring 28 and is of substantially the thickness of the ring.

The ring 28 is of the form shown in Fig. 5, and is cylindrical with its inner periphery so formed as to be divided into four zones, each a portion of a cylinder, the two opposite zones A and B having equal radii with the intermediate opposite zones C and D also having equal radii but shorter than the radii of A and B.

The short sections between adjacent zones have increasing or decreasing radii so that the surfaces of the adjacent zones merge gradually. Further, through the thicker walls of the ring opposite zones C and D will be provided a plurality of axially arranged passages 18A.

The rotor 19 consists of a cylindrical member of an axial length substantially the same as but slightly less than the axial thickness of ring 28. Its radius is somewhat less than the radius of zones C and D of the ring.

The rotor 19 is provided in its periphery with a plurality of slots 19A open to the periphery but of a depth equal to about half a radius. Further, opposite the bottom of each slot 19A and spaced a short distance is an axial through passage 19B. In each of the slots 19A will be a vane 59 such as is shown in Fig. 8. This figure shows a laminated vane of two plates having beveled edges adjacent one face on three sides—the top and two ends. These bevels provide, when the plates are spaced as shown, oil channels leading from the bottom of the slots to the channel at the top. The end channels of course become conduits and the top channel 61 becomes a chamber when the vanes are in the assembly and closely adjacent to or in contact with the face plates 20R and 20L and the ring 28.

A comparatively large central opening surrounded by axially extending bearing flanges 19C, provides for the passage of shaft 15 through the rotor, splines 19D being provided to produce a driving connection between the rotor and shaft.

The face plates 20R and 20L abut the ring 28 and direct fluid flow to and from the rotor. These plates are circular and of the same diameter as ring 28. They have central openings 20A providing bearings for the flanges 19C and are provided with arcuate depressions 20B and 20C in their faces near the periphery. They are also provided with narrower arcuate depressions 20D and 20E adjacent the central opening.

From depressions 20C the large passages 21 open through the face plate so as to open into chamber 13 and from depressions 20D a plurality of small passages 22 also open to chamber 13.

The two plates 20R and 20L are substantially alike except that they are "right" and "left" and when placed in position face to face with the rotor interposed, will be oriented so that a depression 20B of one of them will be opposite a depression 20C of the other.

In addition to the features just described, each of the plates 20R and 20L will be provided in its outer face with a seat for a rubber valve ring 30, the outer edges of which will be clamped between the plates and the bottom of seats 11. The inner edges of valve rings 30 will be clamped between the plates 20R and 20L and a cage element 31 such as is shown in Figs. 6 and 7.

This cage element 31 as shown in these figures, consists of a cylindrical member having a plurality of openings 31A and having at one end a plurality of outwardly extending portions 31B forming functionally a flange adapted to hold the inner edge of valve ring 30 when the parts are assembled. The other end of element 31 will be seated as indicated on a suitable ledge in the wall of chamber 13.

While the above description refers to ring 30 as a single element, it will be cut annularly into two parts, as indicated by the dividing line 30A, of unequal width with the outer part somewhat wider than the inner.

Further, the ring 30 will, as shown, be so seated and clamped that the unsupported area on the side or face adjacent chamber 13 will be greater than that on the other face. By this arrangement, more pressure is required to force fluid through the valve toward the rotor chamber than to force fluid out of this chamber. It should be understood that the valves 30 are identical on both sides.

Referring to Fig. 3, showing the rear or valve face of e. g. plate 20R, F is a valve seat face, G is a channel connecting passages 21, I is an area provided with the passages 22, J is the internally threaded flange receiving a nut 16.

In the operation of the motor, a suitable fluid, preferably oil, under pressure, is led into one of the passages 14 and into e. g. chamber 13. It enters immediately through passages 22 into the depressions (or chambers) 20D and from these directly to the vane slots 19A under the vanes or indirectly through passages 19B and connecting openings 19E.

As the pressure in chamber 13 increases, the valve 30 opens to admit the fluid to the rotor through passages 21 between the vanes to provide the turning movement of the rotor.

The oil entering the passages 21 and 22 flows directly to the vane slots and rotor and also through the passages 19A and 19B to the opposite side of the rotor so that side thrust in the rotor is eliminated or, more correctly, is balanced.

As the rotor turns and the filled vane-produced chambers arrive at the passages 21 in the op-

posite face plate, the pressure of oil under the vanes is released while the oil between the vanes passes out through valve 30.

The result of the use of the valves is to create a pressure differential between that beneath the vanes in the slots and that between the vanes. This pressure difference provides for the positive outward movement at the time of oil inlet and the positive inward movement of the vanes at the time of oil outlet.

The pressure in the passages 22 will, during oil inlet, be higher than the pressure in passages 21 leading to between the vanes. However, the pressure of the vanes against the ring 28 will be less than that behind the vanes because of the balancing chamber 61 in the vane end. At the outlet side the pressure between the vanes will be higher than that in the outgoing passages 22 because of the valve 30 so that there is a positive movement of the vanes inwardly of the slots.

Because of the mounting of the valves 30 as shown, the pressure difference at the inlet side is greater than that at the outlet side, more of the area of the flexible members being supported on the rotor chamber side than on the other.

Further, by providing the through passages 18A in the ring 28 and the through passages 19B in the rotor, the incoming oil under pressure flows to both side faces of the rotor and then to the vanes and slots, thus eliminating side thrust on the rotor.

It should be noted further that by using separate parts 20R and 20L as fluid distributing elements, it is possible to make these and the ring 28 of a different metal or metals than the housing members 10 and 10A. Such construction also enables the valves 30 to be of small bulk and to be so installed as not to interfere with proper fluid flow.

I claim:

1. In a reversible vane type fluid motor a slotted rotor with substantially radially movable vanes in said slots, a single pressure fluid supply leading to said slots under the vanes and to the inter-vane spaces, means to divide the fluid supply between conduit means leading to said slots and conduit means leading to the inter-vane spaces, the latter conduit means including an annular conduit provided with a valve consisting of two concentric annuli of flat flexible material having the inner edge of the innermost and the outer edge of the outermost fixed, and having their adjacent edges abutting.

2. In a reversible vane type fluid motor a slotted rotor with substantially radially movable vanes in said slots, a single pressure fluid supply leading to said slots under the vanes and to the inter-vane spaces, fluid outlet means, means to control said supply whereby the fluid entering said inter-vane spaces is at a lower pressure than that entering said slots and means to control said outlet means to provide for higher pressure in the inter-vane spaces than in the slots, said inlet and outlet control means being interchangeable,

65 each of said control means consisting of a valve consisting of two concentric annuli of flat flexible material having the inner edge of the innermost and the outer edge of the outermost fixed, and having their adjacent edges abutting.

3. In a vane type fluid motor having a radially slotted rotor with radially movable vanes mounted in said slots, a single pressure fluid supply means leading to the slots under said vanes and to the inter-vane spaces, a single fluid outlet for the fluid in said slots and between the vanes,

means in said inlet for partially blocking the flow to the intervane spaces and means in said outlet for partially blocking the flow from said spaces, the first mentioned blocking means adapted to offer greater resistance to flow than the second, said blocking means each consisting of two concentric annuli of flat flexible material having the inner edge of the innermost and the outer edge of the outermost fixed, and having their adjacent edges abutting, the means for fixing the edges of all of said annuli extending over the latter a greater distance diametrically on the face toward the vanes than on the opposite face.
